US00D861737S

(12) **United States Design Patent** (10) Patent No.: **US D861,737 S**
(45) Date of Patent: **** Oct. 1, 2019**

(54) **ELECTRIC FARM TRACTOR**

(71) Applicant: **Mitsubishi Electric Corporation**,
Tokyo (JP)

(72) Inventors: **Takeyuki Hori**, Tokyo (JP); **Tomoaki Tsukada**, Tokyo (JP)

(73) Assignee: **Mitsubishi Electric Corporation**,
Tokyo (JP)

(**) Term: **15 Years**

(21) Appl. No.: **29/593,594**

(22) Filed: **Feb. 10, 2017**

(30) **Foreign Application Priority Data**

Aug. 29, 2016 (JP) 2016-018325

(51) LOC (12) Cl. **12-09**

(52) U.S. Cl.

USPC **D15/23**; D15/199

(57) **CLAIM**

The ornamental design for an electric farm tractor, as shown and described.

DESCRIPTION

FIG. 1 is a perspective view of the front, left and top sides of an electric farm tractor showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a reference perspective view showing the light-emitting portion thereof;

FIG. 9 is a reference view 1 showing the use state thereof, and,

FIG. 10 is a reference view 2 showing the use state thereof. The broken lines in the drawings depict unclaimed environmental subject matter.

1 Claim, 10 Drawing Sheets
